UNITED STATES PATENT OFFICE

HENRY J. KASCH, OF DAYTON, OHIO

HOUSED INDICATOR DIAL

Application filed June 15, 1929. Serial No. 371,131.

This invention relates to rotary indicators and more particularly to a mask or housing enclosing the rotary indicator and means for actuating the rotary indicator within such 5 housing and limiting its degree of movement.

In the present invention there is contemplated a housing or mask which may be of more or less ornamental shape and design 10 and which is recessed upon its rear side to receive a rotary dial. This housing or mask is stationarily secured upon the panel of a radio receiving set or the like in position to overly and enclose the usual rotary dial pertaining to and controlling an adjustable tuning instrument. The mask is provided with 15 an observation opening through which a very limited portion of the graduated margin of the dial may be observed.

At the lower portion of the mask or housing there is provided an adjusting knob the 20 stem of which has frictional engagement with the periphery of the dial. Such adjusting stem is yieldingly held in engagement with 25 the dial by a substantially heart shaped spring. The face of the mask or housing is imperforate except for the observation opening before mentioned, but upon its inner side is provided with a socket into which 30 projects a hub upon the face of the dial. The dial is provided with a stop pin engageable with a lug upon the interior of the mask or housing to limit its range of adjustment.

The object of the invention is to simplify 35 the structure as well as the means and mode of operation of such enclosed and protected indicator dials whereby they will not only be cheapened in construction but will be more efficient in use, capable of being easily and 40 accurately adjusted, of pleasing appearance and unlikely to get out of order.

A further object of the invention is to provide improved means for actuating an enclosed indicator dial.

A further object of the invention is to provide an improved form of spring for the actuating means.

A further object of the invention is to provide means for limiting the range of adjustment of the dial.

With the above primary and other incidental objects in view, as will more fully appear in the specification, the invention consists of the features of construction, the parts and combinations thereof and the mode of operation or their equivalents, as hereinafter described and set forth in the claims.

In the accompanying drawings wherein is shown the preferred but obviously not necessarily the only form of embodiment of the 60 invention, Fig. 1 is a vertical sectional view of an indicator dial and the protecting housing or mask, forming the subject matter hereof, in its assembled relation with the dial.

Fig. 2 is a front elevation of the housing or mask through the observation space of which a portion of the dial graduations appear.

Fig. 3 is a rear elevation of the housing or mask with the dial partly broken away.

Fig. 4 is a face view of the rotary dial removed from the housing.

Like parts are indicated by similar characters of reference throughout the several views.

In the accompanying drawings, 1 indicates 75 the usual rotary indicator dial having at its center a forwardly projecting boss or hub 2 within which is located a slit clutch sleeve 3 for engaging the dial 1 with the rotary shaft of a radio tuning instrument or other device. 80 The rotary disc 1 carries about its periphery a series of graduations 4, as shown in Fig. 2.

Overlying and completely enclosing the dial 1 is a recessed mask or housing 5 having a rearwardly extending marginal flange 6 85 forming a chamber 7 within which the dial 1 is enclosed. The marginal flange 6 abuts upon the face of the mounting panel of the radio set to which it is secured by rearwardly extending studs embedded in the mask or housing 5 and projecting through properly spaced holes in the panel. The mask or housing 5 is stationarily supported wholly independent of the dial 1 which is free to rotate within the interior of the chamber 7. 90

The mask or housing 5 may be of any suitable shape or design. Merely for the purpose of illustration and with no intent to limit the invention to the particular shape or design illustrated, the housing has been shown in 300

the present instance as of substantially shield shape, having a marginal band within which is an annular area having a stippled or matte surface. While not essential to the present invention, the central area of the mask or housing has been shown as bulged forwardly to afford a substantially semi-spherical dome 10 which accommodates and completely encloses and conceals the central hub or boss 2 of the dial and its shaft connection.

The mask or housing thus presents a uniform, continuous, exterior surface beyond which no portion of the dial or its mounting extends. It thus protects the dial and the connection of the dial with the shaft not only against damage or breakage or change of adjustment of the dial upon the shaft, but it also prevents any incidental change of the adjustment of the dial setting, as is likely to occur when the hub of the dial or a knob carried thereby projects beyond the face of the mask or housing.

At the top of the mask or housing 5 is located an observation opening 11 through which graduations 4 upon the face of the dial are visible as the dial is rotated to and fro.

In order to rotate the dial 1 within the housing 5, there is provided upon the lower portion of the mask or housing, an adjusting knob 13, the rear face of which is recessed to receive a forwardly projecting hollow boss 14 formed upon the face of the mask 5. The bore of this hollow boss 14 is inwardly flared in vertical direction, as indicated at 15. The outer orifice of the boss 14 is of substantially circular form and affords a bearing for a rotary stud 16 embedded in the adjusting knob 13 and projecting inwardly through such boss 14. The stud 16 is provided at its inner end with a peripheral groove 17, the sides of which converge inwardly. The periphery of the dial 1 engages in the groove 17 at one side of the stud 16, while a spring 18 maintained under tension with its end resting upon the marginal flange 6, engages the opposite side of the stud 16. By its expansive tendency, the spring 18 tends to press the stud 16 against the periphery of the dial 1. The vertical flare or enlargement 15 of the bore within the hub 14 permits a slight vertical tilting adjustment of the stud 16 relative to the mask or housing into engagement with the dial under the influence of the spring 18. This spring 18 is formed from flat stock and is of substantially heart-shaped contour. The friction drive stem 16 rests in a re-entrant bight formed at the top of the spring on opposite sides of which project upwardly extending bights or lobes of the spring material. The ends of the spring 18 extend downwardly and inwardly, resting upon the marginal flange 6 and abut upon an interposed lug 19 at the bottom of the mask or housing.

65 This type of spring possesses a high degree

of resiliency and uniformity of action. By forming the spring of substantially heart-shape, as illustrated, a much greater length of spring material is included. The spring fits within the lower portion of the mask or housing, resting against the marginal flange 6 where it is held by its reaction against the actuating stud 16. So shaped and positioned, there is but little tendency for the spring to become displaced, and while affording ample driving pressure of the stud 16 upon the periphery of the disc, such resistance is not difficult to overcome in disengaging the stud from the dial or engaging it therewith at the time of assembly.

Within the dome 10 or otherwise centrally disposed relative to the mask or housing, there is provided an annular inwardly projecting flange 20 which forms a socket or blind bearing into which the boss 2 of the dial 1 projects. While this is not an essential feature, it is desirable in properly locating the housing and the dial relative to each other.

Located upon the interior face of the mask or housing 5 is a stop lug 21 with which cooperate studs or pins 22 projecting from the face of the dial 1 to limit its range of revolute adjustment. The dial 1 is preferably, though not necessarily, provided with a plurality of holes in which the studs 22 may be interchangeably engaged. This enables the adjustment to alternate ranges of movement represented by the graduations naught to one hundred and reversely, one hundred to naught, assuming that the dial bears double series of graduations each extending through one half the periphery of the dial, as is a customary marking. Otherwise, by the use of a single stop pin 22, the dial is limited to one complete rotation by the engagement of such pin with the lug 21.

While the mask or housing 5 may be formed from any suitable material such as sheet metal, fiber, pulp, hard rubber or the like, phenolic condensation material is preferred. Such material is not only cheaply and economically molded, but it affords a fine polish surface of pleasing appearance and may be produced in various colors with ornamental surface markings or imitation wood graining. Furthermore, such phenolic condensation material is quite light in weight yet strong and durable and affords ample protection to the enclosed dial.

From the above description it will be apparent that there is thus provided a device of the character described possessing the particular features of advantage before enumerated as desirable, but which obviously is susceptible of modification in its form, proportions, detail construction and arrangement of parts without departing from the principle involved or sacrificing any of its advantages.

While in order to comply with the statute the invention has been described in language more or less specific as to structural features, it is to be understood that the invention 5 is not limited to the specific details shown, but that the means and construction herein disclosed comprise the preferred form of several modes of putting the invention into effect and the invention is, therefore, claimed in any 10 of its forms or modifications within the legitimate and valid scope of the appended claims.

Having thus described my invention, I claim:

1. In an apparatus of the character described, a rotary dial or the like, a revolute actuating stem having driving engagement with the dial, a mounting therefor, and a substantially heart-shaped spring having a 20 medial re-entrant bight in which the actuating stem rests.

2. In an apparatus of the character described, a rotary dial or the like, a revolute actuating stem having driving engagement with the dial, a mounting therefor, a bow 25 spring the ends of which approach one toward the other, and a lug upon the mounting forming opposite stop shoulders against which the ends of the spring abut, the medial portion of said bow spring bearing against 30 the side of the actuating stem opposite its engagement with the dial.

3. In an apparatus of the character described, a rotary dial or the like, a revolute actuating stem having driving engagement 35 with the dial, a mounting therefor, and a length of spring material bent into a succession of reverse bights, in one of which bights the actuating stem rests with adjacent oppositely disposed bights of such spring 40 material extending on opposite sides of the stem, the ends of the length of spring material being seated upon said mounting.

4. In an apparatus of the character described, a rotary dial or the like, a revolute actuating stem having driving engagement 45 with the dial, a mounting therefor, and a length of spring material having a medial bight formed therein in which the actuating stem rests, the ends of the length of spring 50 material being inturned toward each other and engaged with said mounting.

5. A housing for a radio dial or the like comprising a mask overlying the dial and having an observation opening therein 55 through which graduations upon the dial may be observed, means for rotating the enclosed dial, a stop lug formed upon the inner face of the mask and stop pins carried in spaced relation by the dial and alternately engageable with the stop lug to limit the 60 range of rotation of the dial.

6. A housing for a radio dial or the like comprising a mask overlying the dial and having an observation opening therein 65 through which graduations upon the dial

may be observed, means for rotating the enclosed dial, of a stop lug located interiorly of said housing, said dial having a series of spaced holes therein and a stop pin engageable in any one of the holes of the series and 70 engageable with the stop lug upon rotation of the disc to limit the range of adjustment thereof.

7. A housing for a radio dial or the like comprising a mask overlying the dial and 75 having an observation opening therein through which graduations upon the dial may be observed, means for rotating the enclosed dial, a stop lug located interiorly of said housing, said dial having two pairs of 80 spaced holes therein, one pair of holes being located on each side of the center of the disc in substantially diametrically opposed relation, and a pair of pins interchangeably engageable in said holes. 85

8. A housing for a radio dial or the like comprising a mask overlying the dial and having an observation opening therein through which graduations upon the dial may be observed, means for rotating the enclosed dial, a journal bearing in said housing, and an integral projecting bearing portion on said dial engaged therein, whereby the dial is revolvably supported upon the 90 housing independent of other supporting 95 means.

9. A housing for a radio dial or the like comprising a mask overlying the dial and having an observation opening therein through which graduations upon the dial 100 may be observed, means for rotating the enclosed dial, said dial bearing two reversely disposed series of graduations distributed respectively over the opposite halves of the dial, a stop lug located within the housing, 105 and stop pins located in proximate relation with the limits of the respective series of graduations adapted to alternately engage the stop lug on opposite sides to limit the range of revolute adjustment of the dial 110 to one series of graduations.

In testimony whereof, I have hereunto set my hand this 1st day of June, A. D. 1929.

HENRY J. KASCH.
